UNITED STATES PATENT OFFICE.

CHARLES LEET EDWARDS, OF VERNON, NEW YORK.

EXPLOSION-ENGINE.

No. 878,364.

Specification of Letters Patent.

Patented Feb. 4, 1908.

Application filed March 8, 1907. Serial No. 361,214.

To all whom it may concern:

Be it known that I, CHARLES LEET EDWARDS, a citizen of the United States, and resident of Vernon, in the county of Oneida 5 and State of New York, have invented an Improved Explosion-Engine, of which the following is a specification.

My invention is an improvement in explosion engines, and consists in certain novel 10 constructions and combinations of parts hereinafter described and claimed.

Referring to the drawings forming a part hereof, Figure 1 is a vertical section through my improved engine. Fig. 2 is an enlarged 15 detail of the upper end of Fig. 1, showing the valves in one position. Fig. 3 is a similar view showing the valves in another position. Fig. 4 is a similar view showing the valves in another position. Fig. 5 is a view of one 20 form of cam for operating the valves. Fig. 6 is a view of another form of cam. Fig. 7 is a plan view of the inlet valve, and Fig. 8 is a detail view of a part of the pull rod used with the cam of Fig. 6.

25 In the present embodiment of my invention, the cylinder 1 is jacketed as at 2, and the piston 3 is connected by the piston rod 4 with the crank arm of the drive shaft 5. The drive shaft is provided with fly wheels 6 and 30 with the toothed portion 7 meshing with the pinion 8 secured to a cam shaft 9 journaled in the casing of the engine, and provided on its outer end with a cam 10^a for a purpose to be hereinafter described.

35 The cylinder is provided with an opening at one end, and formed in the opening is an inner conical valve seat 11 and an outer cylindrical valve seat 12. An inlet port 13 communicates with the opening on one side 40 of the cylinder, and an exhaust port 14 communicates with the opening on the opposite side of the cylinder. At the end of the cylinder is a valve stem guide 15, provided at its inner end with a petticoat 16 for a purpose to be hereinafter described.

45 The inlet valve 17 moves in the cylindrical seat, and the said valve is provided with a plurality of openings 18 therethrough, and with a peripheral flange 19, of a depth sufficient to close the exhaust port when the said inlet valve is depressed, as shown in Fig. 4. The openings 18 through the inlet valve are closed by the petticoat 16 when the inlet valve is in its normal position, and the stem 50 20 of said valve extends outwardly through the stem guide 15 and is provided on its

outer end with a collar 21 for a purpose to be hereinafter described.

The exhaust valve 22 engages the conical seat 11, and the stem thereof extends 60 through the stem 20 of the inlet valve, and is provided on its outer end with a collar 22^a of greater diameter than the collar 21, and spaced apart therefrom:

A spiral spring 23 is arranged between the 65 collar 21 and the end of the cylinder, and a second spring 24 is arranged between the collar 22^a and the end of the cylinder, the second spring being concentric with the first spring, and of greater strength for a purpose 70 to be hereinafter described. A lever 25 is pivoted to the engine frame near the end of the cylinder, one end of said lever engaging the collar 22^a on the end of the exhaust valve, and the other end of the lever is engaged by a 75 push rod 26 mounted to slide on the frame and engaged at its opposite end by the cam 10^a before mentioned.

If it is desired to make use of a pull rod for 80 opening the valve, instead of a push rod, the cam shown in Fig. 6, is made use of, and instead of using a pivoted lever as shown in the above described construction, a slidable rod 27 is made use of, the said rod having an angular portion 28 adapted to engage the 85 collar of the valve stem, and the pull rod is normally maintained in contact with the cam by means of a spring 29, the operation of the remaining parts being the same in both cases. 90

In operation, when the exhaust valve is first opened, the products of combustion are permitted to escape through the exhaust outlet to the outside air, the push rod being engaged at this time by the portion 31 of the 95 cam 10^a. As soon as the piston commences its forward stroke, the push rod is engaged by the portion 32 of the cam, thus continuing the opening motion of the exhaust valve, until the collar 22^a thereon engages the collar 21 100 of the inlet valve, after which the inlet valve partakes of the motion of the exhaust valve, and is moved inward to cover the exhaust port, and to move the inlet valve away from the petticoat whereby to uncover the openings through said valve, thus permitting the 105 charge to be drawn into the cylinder by the piston.

In the use of the pull rod, and the cam 11^a, the exhaust valve begins to open when the 110 pull rod is engaged by the part 33 of the said cam, and both valves are opened by the en-

gagement of the pull rod with the portion 34 of the cam. The latter form of cam and pull rod is preferable in cylinders provided with an auxiliary exhaust, while the former construction is preferred in cylinders not so provided.

It will be observed that the incoming cool charge passes over the heated exhaust valve, thus cooling the same and further vaporizing the said charge. The inrushing charge also acts to clean the exhaust valve and to prevent scaling. By providing a spring of greater strength for the exhaust valve, the said valve will move quickly against the inlet valve at the return motion thereof, thus closing the inlet. Bosses 40 are arranged on the lower face of the inlet valve for retaining said inlet valve at all times slightly out of contact with the exhaust valve.

20 I claim:

1. In an explosion engine, the combination with a cylinder provided with a water jacket, and having in the end thereof an opening in which are formed an inner 25 conical and an outer cylindrical valve seat, and having an inlet port and an exhaust port communicating with the opening, of an exhaust valve, normally resting on the conical seat and closing the opening, said valve having a stem extending out of the cylinder, said cylinder being provided with a valve stem guide provided on its inner end with a petticoat, an inlet valve having a plurality of openings therethrough, normally 30 closed by the petticoat, said valve moving in the cylindrical seat, and having a stem encircling the exhaust valve stem, said valve having a peripheral flange adapted to close the exhaust port, when moved away from the petticoat, concentric springs resting at 35 their inner ends against the cylinder, and encircling the valve stems, the outer spring being of greater strength than the inner spring, a collar on each of the stems for engaging the outer ends of said springs, the 40 collar on the exhaust valve stem being of greater diameter and engaging the stronger spring, said collars being spaced apart whereby the continued movement of the exhaust 45 valve stem after the opening of the exhaust port will move the inlet valve to close the

exhaust port and to open the inlet port, a drive shaft, a piston in the cylinder and connected therewith, and a connection between the drive shaft and the valve stem for operating the same at regular intervals.

2. In an explosion engine, the combination with a cylinder having an end opening in which are formed an inner conical and an outer cylindrical valve seat, and having inlet 60 and exhaust pipes communicating with the opening, of an exhaust valve normally resting on the conical seat and closing the opening, said cylinder being provided with a valve stem guide having at its inner end a 65 petticoat, an inlet valve having a plurality of openings therethrough normally closed by the petticoat, the said valve moving in the cylindrical seat, and having a peripheral flange adapted to close the exhaust port 70 when moved away from the petticoat, springs acting to seat said valves, a drive shaft, a piston in the cylinder connected with the drive shaft, means whereby the drive shaft may open said exhaust valve at 75 predetermined intervals, and means whereby the exhaust valve may open the inlet valve when said exhaust valve is fully opened.

3. In an explosion engine, the combination with a cylinder having an end opening 80 in which are formed an inner conical and an outer cylindrical valve seat, and having inlet and exhaust pipes communicating with the opening, of an exhaust valve normally resting on the conical seat and closing the opening, said cylinder being provided with a valve stem guide having at its inner end a 85 petticoat, an inlet valve having a plurality of openings therethrough normally closed by the petticoat, the said valve moving in the 90 cylindrical seat, and having a peripheral flange adapted to close the exhaust port when moved away from the petticoat, springs acting to seat said valves, means for 95 opening the exhaust valve at predetermined intervals and for opening the inlet valve at the end of the opening movement of the exhaust valve.

CHARLES LEET EDWARDS.
